UNITED STATES PATENT OFFICE.

FOSTER J. HULL, OF BROOKLYN, NEW YORK, ASSIGNOR, BY MESNE ASSIGNMENTS, TO AMERICAN MECHANICAL CASHIER COMPANY, A CORPORATION OF NEW JERSEY.

CHECK-SEVERING DEVICE.

SPECIFICATION forming part of Letters Patent No. 710,360, dated September 30, 1902.

Application filed September 20, 1901. Serial No. 76,007. (No model.)

To all whom it may concern:

Be it known that I, FOSTER J. HULL, a citizen of the United States, residing at Brooklyn, in the county of Kings and State of New York, have invented certain new and useful Improvements in Check-Severing Devices, of which the following is a specification.

This invention relates to check-severing devices for mechanical cashiers or recorders and similar machines; and its object is to provide means whereby the act of insertion or withdrawal of a check or slip in or from the machine will result in severing the slip.

This invention is particularly intended for use in connection with mechanical cashiers or cash-recorders wherein a check-slip is used having a main body portion and a coupon or voucher portion, both of which are printed on by the action of the machine and which are required to be severed for any reason—for example, in order to enable the coupon to be retained by the cashier or machine or by the operator.

The invention comprises, in connection with a mechanical cashier or cash-recorder, means for supporting a check-slip and inserting it in and withdrawing it from the machine and severing means operated by such operating means to sever the slip in the manner stated.

In the accompanying drawings, Figure 1 is a plan view of check-severing mechanism embodying my invention. Fig. 2 is a front elevation thereof. Fig. 3 is a side elevation. Fig. 4 shows another form of my invention in front elevation.

The mechanical cashier or recorder to which this invention is applied may be of any usual or special construction, and the various operative parts of the same, including the recording bars or devices, platen mechanism, &c., are not herein shown, as they form no part of my present invention. 1 represents a portion of the base of such a machine, and 1' 1" two frame-plates projecting from said base, which constitute the support for the check carrying and severing devices now to be described.

The check or record-slip carrier consists of a sliding table or support 2, movable in suitable guides in the aforesaid frame-plates and

provided with spring plate or shield 3 to hold down the slip placed on said carrier and with a raised rim or gage-flanges 4, which, in connection with the shoulder 3' of the spring-plate 3, serve to properly position the record-slip on the carrier. Slots 5 in the carrier may serve for the passage of suitable printing devices. (Not shown.) The carrier is also provided with a slot 6, extending through both the body of the carrier and the overlying spring-plate 3, so as to enable free access to the record-slip from top and bottom by the cutting devices. Said cutting devices comprise two rotary knives or cutting-disks 8 9. The lower disk 8 is fast on a shaft 7, journaled in a fixed support below the carrier 2 and having fixed to it a pinion 8', engaged by a rack 10 on the under side of the carrier, so that if the carrier or support 2 is pushed in or pulled out it will rotate this lower cutting-disk. The upper cutting-disk is shown in Figs. 1 to 3 as mounted to rotate freely on a bracket 13, pivoted to frame-plate 1" above the carrier 2 and drawn by a spring 11 in such manner as to hold the upper cutting-disk 9 with its periphery bearing yieldingly against the periphery of the lower cutting-disk 8. The cutting-disks 8 9 overlap slightly, so that the peripheral portions of their adjacent sides bear against one another and tend to give a shearing or drawing cut. I prefer to mount the upper cutting-disk 9 at a slight angle both horizontally and vertically to the lower cutting-disk, as the cutting action is thereby rendered more effective. In this form (shown in Figs. 1 to 3) the upper disk is caused to rotate by friction with the lower disk. When the record-slip is placed on the carrier 2 and the latter is pressed in, it carries the slip between the rotary knives or cutters 8 9, and thereby causes the slip to be severed in an obvious manner. One of the severed portions may then be retained in the machine by any suitable means, or, if desired, it can remain on the carrier and be retained by the operator when the carrier is pulled out.

In the modification shown in Fig. 4 the construction of the cutters is the same as above described, except that means are provided for positively driving the upper cutter, such

means being here shown as consisting of engaging gears 12 12', one of which is connected to the lower cutter-disk, while the other is connected by a flexible shaft 7' with the upper cutting-disk 9, whereby said upper cutting-disk is caused to rotate positively in obvious manner.

Having thus described my invention, the following is what I claim as new therein and desire to secure by Letters Patent:

- 5 1. The combination with a movable slip-carrier, of a slip-severing device connected to and operated by the movement of said carrier.
- 10 2. In a machine of the character described, the combination with a movable carrier for supporting a removable slip and inserting it within the machine, of a severing device operated by the movement of the carrier to sever the slip.
- 15 3. In a machine of the character described, the combination of a sliding support movable and guided in said machine and adapted to receive a slip and insert same in the machine, of a severing device located in fixed relation to the machine and having operating connec-

tions with the carrier whereby movement of the carrier operates the severing device to sever the slip.

4. The combination with a slip-carrier and a severing device consisting of engaging rotary knives, one of which is operatively connected with said carrier. 30

5. The combination with a slip-carrier and a severing device consisting of engaging rotary knives, both of which are operatively connected with said carrier. 35

6. The severing device comprising two rotary knives engaging by the peripheral portions of their sides, and means for yieldingly drawing one of said knives into engagement 40 with the other.

7. The combination with the movable slip-carrier of the two rotary slip-severing knives, a gear connected to one of said knives, and a rack connected to the slip-carrier and operating said gear to turn the knives. 45

FOSTER J. HULL.
